ICE CRUSHER AND CONVEYOR

Filed June 6, 1945

UNITED STATES PATENT OFFICE

2,416,431

ICE CRUSHER AND CONVEYOR

Frank W. Brady, San Francisco, Calif.

Application June 6, 1945, Serial No. 597,826

1. Claim. (Cl. 241—101)

1. This invention relates to improvements in ice crushing and conveying machinery.

In the packaging of commodities such as lettuce for marketing it is usual to include in a crate, or other container for the commodity, a considerable portion of finely divided ice to which the term "snow ice" is usually applied. Ice is delivered to the packing shed in the forms of large blocks, each usually weighing about 300 pounds. Each block is broken up into smaller chunks and these are placed in an ice crusher, the finely divided ice being removed from the crusher by horizontal conveyor which feeds into a vertical conveyor, the latter delivering the ice to a conveyor system which moves the ice to a desired point in the packing shed. Because of the necessity for driving the ice crusher and the several conveyors by separate prime movers it has been usual heretofore to install the ice crusher on a separate foundation and at an elevation above the shed floor. This necessitates the lifting by hand of the ice to be crushed into the crusher. The finely divided ice was removed from the bottom of the crusher by means of a horizontal screw, the latter delivering the material to a vertical screw. To drive the two screws, a complicated drive arrangement was required. I have found that the crusher can be placed at the floor level and a single conveyor utilized, if the axis of the crusher drum and of the screw conveyor are placed parallel to one another, the ice crusher ice receiving inlet being placed at the floor level so that the ice blocks can be slid along the floor and so fed to the crusher inlet.

It is in general the object of the present invention to provide an improved ice crusher conveyor construction such as is utilized in packing house machinery.

A further object of the present invention is to provide a simplified ice crusher and snow ice delivery device.

The invention includes other objects and features of advantage, some of which, together with the foregoing, will appear hereinafter wherein the present preferred form of ice crusher of this invention is disclosed. Referring to the drawing accompanying and forming a part hereof, Figure 1 is a side elevation, partly in section, showing the device of the present invention installed in a packing house. Figure 2 is a section taken along the line 2—2 in Figure 1.

Figure 3 is a plan view of the ice crusher drum with a portion broken away.

Referring to the drawing, the device includes a suitable housing structure made up of steel

plates welded together, the housing being generally indicated by numeral 6. An ice crusher drum generally indicated by numeral 7 is mounted upon a shaft, 8, the latter being carried in bearings, 9, mounted upon opposite sides of housing 6. Shaft 8 extends through the bearings, being connected on one side to a pulley 11, about which is trained a belt 12, the latter also passing about a pulley 14 on shaft 16 of electric motor 17, the latter being carried upon portion 20 of the housing 6.

About the periphery of the ice crusher drum 7 are mounted a plurality of breaker points or teeth 18. The drum includes a plurality of spokes 19 extending from a central hub 25 mounted on shaft 8.

As appears in Figure 2, housing 6 is fashioned with an inlet 21 and a deflector plate 22, the latter serving to direct ice admitted by inlet 21 to the drum. The inlet includes a horizontal plate 24, the latter forming a portion of the housing structure and being connected thereto by side plates 26, so that when plate 24 is positioned on the floor 27 of a packing shed, the entire structure is adequately supported at the inlet end thereof.

Ice crushed by the drum cooperating with the deflector plate 22 is directed downwardly by plates 28 and 29 provided on each side of the housing into an annular portion of 31 cooperating with a screw conveyor flight 32 mounted upon a shaft 33. Beyond the housing 6, the screw conveyor flight is confined by a conduit 34, the latter being supported intermediate its end by a suitable foot 36 engaged with the floor 27, and supporting the screw conveyor casing and providing additional support for the housing.

Screw conveyor shaft 33 is supported by bearings 37 and 38, bearing 37 being provided on housing 6 while bearing 38 is provided upon plate 39 at the discharge end of conduit 34. A sprocket 41 is positioned on an end of shaft 8 and a chain 42 is passed about this sprocket and a sprocket 43 on the screw conveyor shaft 33. This enables the screw conveyor to be driven directly from the ice breaker drum shaft so only one prime mover is required.

At the upper end of conduit 34, a discharge chute 46 is provided so that ice delivered from the screw conveyor flight can be discharged into another conveyor or into a suitable receptacle.

In providing the device, it is only necessary to cut a suitable hole in the packing house floor to permit the depending portion of the housing 6, and the screw conveyor casing 34 to be inserted, the entire structure being then supported

by the packing house floor. If desired, an additional support can be provided as at 51, an angle iron 52 being positioned at the lowest point on the housing 6. However, this is not necessary.

It will be observed that housing 6 and screw conveyor casing 34 are formed as a unit. Shafts 33 of the screw conveyor flight and shaft 8 of the ice breaker drum are in alignment; a simple chain and sprocket drive suffices between them. The ice inlet is horizontal while shafts 8 and 33 are positioned at an angle of 45° to the floor 27. This angle is preferred since, for a given power input, the crusher drum disposes of more ice. The angle is not critical in that it can be varied without affecting the operation to too great an extent if it is necessary to adjust the angle in a given installation to suit local conditions.

I claim:

In combination with a floor over which ice blocks are supported prior to crushing, a receptacle, said receptacle being provided with a plate extending substantially parallel to the plane of said floor and comprising a support for said receptacle, a pair of vertically extending spaced side plates secured to said plate and said receptacle and forming guides for said ice blocks, an ice crusher rotor mounted in said receptacle, said receptacle being provided with an inlet to said crusher, said inlet being disposed to one side of said receptacle, an inclined deflector plate mounted in said receptacle and having one of its ends positioned adjacent said crusher, said crusher rotor comprising a drum mounted on a

5 shaft extending at an angle to said floor, a screw conveyor including a screw rotatable in a conduit to move ice from the drum to a point elevated above said floor, said screw and said shaft being parallel, said screw conveyor being partially supported by said floor, a prime mover including a rotatable drive shaft, said prime mover being mounted on said receptacle adjacent said inlet, said drive shaft, said screw, and 10 crusher drum shaft being parallel, means connecting said drive shaft with one end of said crusher drum shaft, and means for driving said screw from the other end of said crusher drum shaft.
